UNITED STATES PATENT OFFICE.

ARTHUR TREVOR DAWSON, GEORGE THOMAS BUCKHAM, AND CARL ALFRED LARSSON,
OF WESTMINSTER, LONDON, ENGLAND, ASSIGNORS TO VICKERS LIMITED, OF LON-
DON, ENGLAND.

AUTOMATIC GUN.

Application filed May 21, 1923. Serial No. 640,568.

To all whom it may concern:

Be it known that we, ARTHUR TREVOR DAWSON, GEORGE THOMAS BUCKHAM, and CARL ALFRED LARSSON, all subjects of the 5 King of Great Britain, residing at Vickers House, Broadway, Westminster, in the county of London, England, have invented certain new and useful Improvements in or 10 Relating to Automatic Guns, of which the following is a specification.

This invention relates to automatic guns of the barrel recoiling type in which the lock is connected by toggle levers (constituted by a connecting rod and a crank) 15 to a part recoiling with the barrel. The invention is particularly applicable to the Vickers automatic gun provided with the usual belt feed or with a drum feed.

As is well known it is customary in loading guns of the above type prior to firing, to twice actuate the handle connected to the crank shaft in order to insert a cartridge in the barrel and in the case of a belt feed it is also necessary to push or pull the belt 25 a step forward between the two actuations of the crank handle, these various operations being required owing to the fact that the barrel remains stationary. The chief object of the present invention is to provide 30 improved means for manually retracting the barrel so as to simplify the loading operation.

According to the invention the mechanism casing is provided with a stop-piece 35 serving as a fulcrum for a part moving with the crank shaft so that when the crank handle is being operated by hand the said part will come against the stop-piece and the continued operation of the crank handle 40 will then effect the retraction of the barrel. The said stop-piece is made movable and is caused to assume an inoperative position when the trigger is operated to fire the gun; the movement of the stop-piece is preferably 45 controlled by the trigger mechanism in such a manner that the actuation of the trigger to fire the gun positively effects the movement of the stop-piece to its inoperative position and the release of the trigger to stop 50 firing permits the stop-piece to assume its operative position.

In order that the said invention may be clearly understood and readily carried into

effect, the same will now be described more fully with reference to the accompanying drawings, in which:—

Figures 1 and 2 are respectively a vertical longitudinal section and a plan with the mechanism casing cover removed, of the rear part of an automatic gun provided with a constructional form of our invention.

A is the mechanism casing, A¹ the crank and A² the connecting rod, the crank being connected to a shaft A³ carried by the recoil plates of the gun barrel as is well understood. A⁴ is the usual operating crank handle connected to the shaft A³. B is the trigger operating through a pivoted lever B¹ upon a trigger bar B² slidably carried by the hinged rear cover a of the mechanism casing as is customary. C represents the aforesaid movable stop-piece which, in the example shown, is in the form of a spring-controlled plunger arranged transversely at the lower part of the mechanism casing at a suitable distance in front of the rear wall thereof. Normally (i. e. when the gun is not firing) the end of the plunger C protrudes beyond the mechanism casing as shown in Figure 2 for engagement with the tail a⁴ of the crank handle A⁴. The said plunger is connected by a bell crank lever b and links b¹ to a lever b² the upper arm of which is arranged in front of the lower arm of the trigger lever B¹ so that the plunger is retracted into its inoperative position out of the path of the tail of the crank handle when the trigger B is actuated to fire the gun. To load the gun prior to firing, the crank handle A⁴ is partially rotated to break the toggle levers formed by the crank A¹ and the connecting rod A² and bring the lower surface of the crank handle tail a⁴ against the plunger C; continued movement of the crank handle then retracts the barrel owing to the fact that the crank shaft A³ is carried by the recoil plates connected to the barrel. Before the maximum recoil position of the parts is reached the tail a⁴ clears the plunger C and the parts are then free to return under the action of the recoil spring. The forward portion of the protruding end of the plunger is bevelled as shown in order to permit the tail to pass the plunger in returning to the normal position.

What we claim and desire to secure by Letters Patent of the United States is:—

- 5 1. In an automatic gun of the barrel recoiling type, the combination with the operating crank, of a part moving therewith and a stop-piece carried by the non-recoiling mechanism casing of the gun serving as a fulcrum for the said part so that when the crank handle is being operated by hand the 10 said part will come against the stop-piece and the continued operation of the crank handle will then effect the retraction of the barrel.
- 15 2. In an automatic gun of the barrel recoiling type, the combination with the elements claimed in claim 1 of means for moving the stop-piece to an inoperative position when the trigger is operated to fire the gun.
- 20 3. In an automatic gun of the barrel recoiling type, the combination with the elements claimed in claim 1 of means for positively moving the stop-piece to an inoperative position by the movement of the trigger 25 to fire the gun, and means for returning said stop-piece to its operative position when the trigger is released.
4. In an automatic gun of the barrel recoiling type, the combination with the operating crank and crank handle, and a tail 30 on said crank handle, of a spring controlled plunger carried by the mechanism casing of the gun and normally projecting into the path of said tail and means for connecting said plunger to the trigger of the gun so 35 that when the trigger is operated to fire the gun said plunger will be positively moved out of the path of said tail.
- 40 5. In an automatic gun of the barrel recoiling type, the combination with an operating crank journalled in the recoiling mechanism, of a part moving therewith and a stop-piece carried by the non-recoiling mechanism casing of the gun and serving 45 as a fulcrum of the said part so that when the crank handle is operated by hand the said part will come against the stop piece and the continued operation of the crank handle will then effect the retraction of the barrel.

ARTHUR TREVOR DAWSON.
GEORGE THOMAS BUCKHAM.
CARL ALFRED LARSSON.
